UNITED STATES PATENT OFFICE

2,573,411

ABRASIVE DISK BACKUP PAD

Frank De Michel, Chicago, Ill.

Application June 3, 1948, Serial No. 30,897

4 Claims. (Cl. 51—197)

1

My invention relates to an improvement in abrasive disk backup pads and more specifically to a pad which is air cooled and may be considered an improvement over the pad disclosed in my copending application, Serial No. 791,301, filed December 12, 1947.

One object of my invention is to provide an improved backup pad which will minimize the accumulation of frictional heat.

Another object of my invention is to provide a novel, flexible backup pad making provision for cooling its associated sandpaper.

Still another object is to provide a backup pad in which the stiffening members are incorporated in a novel and improved fashion.

Yet another object is to provide a novel device consisting of a backup pad which incorporates secondary mounting means to permit easy removal from the driving spindle for substitution thereof and yet which is retained on the spindle sufficiently strong to facilitate the changing of abrasive disks.

Other objects and advantages of my invention will become apparent from the following description and drawings, of which:

Fig. 1 is a plan view of the face of the pad embodying my invention, shown without the nut which holds the paper;

Fig. 2 is an elevational view of the edge of the pad;

Fig. 3 is a sectional view which may be considered as being taken substantially along the line 3—3 of Fig. 1 looking in the direction of the arrows;

Fig. 4 is a plan view of the under side of the central portion of the pad showing the hub and the plate structure immediately surrounding it;

Fig. 5 is a plan view of one of the stiffening laminations incorporated in the plate; and

Fig. 6 is a perspective view of the type of bolt employed in the practice of my invention.

In its preferred embodiment, my invention comprises a hub 10 having a threaded opening 12 extending therethrough which is adapted to be mounted on the threaded end 14 of a rotatable power driven shaft 16. The outer surface of the hub is flared outwardly and upwardly to provide a flange 18 offering a large diameter supporting surface 20 for the plate 26. A cylindrical projection 22 concentric with the shaft opening and slightly spaced therefrom extends upwardly from the surface 20. Outside the projection is a ring of tapped holes 24 extending through the flange 18 to open on either side thereof.

The plate 26 comprises a plurality of flexible, thin circular sheets 28 of varying diameter, pref-

2

erably made of metal, fiber or phenolic material. Each of these sheets is punched to provide a plurality of perforations 30 therein arranged in regular order and the sheets are then stacked in a shallow conical arrangement. Rubber laminations 32 are interspersed between the members of the stack and a coating of tough heat-resistant rubber is molded thereabout, the heat and pressure of the molding being sufficient to bond the coating and the laminations to the stacked sheets and to link the laminations through the perforations 30. In this fashion a plate of controlled flexibility is obtained in which the supporting members are firmly integrated with the whole. The plate is drilled to provide a central opening 36, whereby the plate may be mounted on the projection 22 of the hub, and a plurality of ports 38 annularly surrounding the central opening to align with the tapped holes 24 in the hub when the plate is mounted thereon.

In the molding process, the face of the plate is formed to provide a central recessed portion 40 intended to accommodate the nut 42 so that it may be flush with or below the surface of the face. In this depressed portion a solid annulus 44 immediately surrounds the opening 36 which is bounded on its outer edge by a passage 46 passing through the centers of the ports 38 concentric with the ports. The rubber is removed from the surface of the upper sheet to provide bolt head seats 48, the diameter of the rubber removal being greater than that of the bolt head. Outwardly of the passage 46 a plurality of outwardly directed ribs 50 is formed, the outer portions 52 of which lie at the face level and the inner ends 54 of which are inclined downward to the level of the depressed portion 40. Outwardly of these ribs is located an outer passage 56 and outwardly of the passage lies a second series of ribs 58 terminating on the outer edge of the plate. These ribs and annular passages form a system of intercommunicating, generally radial, closely spaced passages 60 extending from the holes 38 to the periphery of the plate.

The coating on the underside of the plate is molded to provide an integral mounting ring 62 which consists of an annular protrusion 64 and a lip 66 extending inward from the top of the protrusion. The inside diameter of the protrusion is slightly larger than and the inside diameter of the lip smaller than the hub flange 18, such that the ring may be slipped over the flange to provide a loose and easily detached secondary mounting means for a purpose to be subsequently described.

The type of bolt 68 preferably employed to se-

cure the plate to the hub is illustrated in Fig. 6. It is characterized by a head 70 having cross slots 72 thereon and a hole 74 extending axially throughout the length of the shaft 76. The shaft is externally threaded to seat in the tapped holes 24 of the hub.

The nut 42 is the type conventionally employed in abrasive disk backup pads and consists of a short tubular section 78 threaded on its inner surfaces to co-operate with the threaded shaft 14 and having a wide annular flange 80 formed on the upper end thereof.

In use the plate may or may not be bolted to the hub depending on whether it is anticipated that the pad will be changed frequently, for example, to mount a plate of another size. The advantage in using the bolts, of course, is to insure correct alignment of the hub holes 24 and the ports 38. If bolts are to be employed they may be placed in all or some of the accommodating holes. Two bolts would be the minimum consonant with preserving the balance of the pad. The hub, in any case, is threaded on the shaft and the plate seated on the hub. Alignment of the ports and holes is accomplished by the bolts or by manual orientation.

The sandpaper disk 82 to be employed with this pad is of the conventional type having an axial hole therein adapted to fit closely about the shaft 78 of the nut. It will usually be fitted to the nut and the nut then screwed down on the threaded shaft end 14 until the paper is firmly secured between the nut flange 80 on one side and the ring 44 and inner rib ends 54 on the other. It will be noted that the plate is thus locked in the assembly whether or not the bolts are employed.

As power is applied to the shaft and the disk is brought to sanding velocity, centrifugal force is imparted to the air in the passages 60 on the face of the pad, starting a flow through the pad. Air enters the passages at the inner ends thereof or through the hollow bolts 68 or, where bolts are not used, through the bolt holes 24 and ports 38 in the hub and plate, passes through the slots 72 of the bolt heads into the annular space 84 provided between the bolt head and the oversized bolt head seat 48 and thence into the annular passage 46 and radial passages 60 to expulsion from the periphery of the pad.

In the event that two or three bolts only are employed to secure the hub and plate together, conventional bolts will serve, the unused bolt holes providing the air intake.

The mounting ring 62 is of importance when the work being performed involves changing of plates, in which situation the plate is not bolted to the hub. When the abrasive disk needs replacement, the removal of the nut would normally result in the plate falling off the hub or, at least, making retention thereon difficult and disk replacement awkward. The mounting ring serves as a loose connection between the two members whereby the plate is retained in position on the hub despite the removal of the nut. On the other hand, the lip of the ring is sufficiently resilient and overlaps the flange of the hub sufficiently slightly so that the plate may easily be separated from or installed on the hub.

Having described my invention, what I claim as

new and useful and desire to secure by Letters Patent of the United States is:

1. An abrasive disk backup pad adapted to be mounted on a powered spindle and to have an abrasive disk mounted on the face thereof, including a plate and a hub for said plate adapted to be mounted on said spindle, said plate having a plurality of elevations on the face thereof defining a series of air passages extending from the inner portion of said face generally outward to open to the periphery thereof, said plate and said hub having a plurality of aligned ports there-through communicating with the inner end of said passages, and tubular securing members situated in a plurality of said ports to link said hub and said plate together and admit air to the inner end of said passages.

2. A flexible abrasive disk backup pad comprising a plurality of resilient circular supporting elements of varying diameter arranged so that the element of greatest diameter lies adjacent the face of said pad and the remaining elements are stacked in the order of diminishing diameter away from said face, each of said elements being comprised of one or more resilient, thin, circular, dimensionally stable plates, flexible rubber-like interleaving between said circular plates, a flexible heat resistant coating molded about said stack, and means forming openings through said pad to link operatively said pad to a powered shaft.

3. A flexible abrasive disk backup pad adapted to have an abrasive disk mounted on the face thereof comprising a plurality of resilient circular supporting elements of varying diameter arranged concentrically so that the element of greatest diameter lies adjacent the face of said pad and the remaining elements are stacked in the order of diminishing diameter away from said face, each of said elements being comprised of one or more resilient, thin, dimensionally stable, circular, perforated plates, rubber-like interleaving separating all the plates in said stack bonded together through the perforations in said plates, a flexible heat resistant coating for said stack molded thereabout to contain said stack and to unite with the interleaving through the perforations in the outer plates, and means forming openings through said pad to link operatively said pad to a powered shaft.

4. In a plate for an abrasive disk backup pad adapted to be held on a powered spindle by retention between a hub on the underside thereof and a sandpaper nut on the face thereof, a mounting ring comprising an outstanding inwardly turned circular flange of a resilient material on the underside of said plate conformed to engage the adjacent periphery of said hub.
